METAL SKIMMING LADLE

John E. Weiler, Lake Charles, La., assignor to
 The Mathieson Alkali Works, Inc., New York,
 N. Y., a corporation of Virginia

Application October 28, 1942, Serial No. 463,577

1 Claim. (Cl. 266—37)

1

This invention relates to the production of light metal from salt fusions and has for its object the provision of an improved ladle for removing the molten metal from the place where it is produced or collected and separating it from the fused salt. In the production of light metal, for example by the electrolysis of fused salt, the metal is usually collected in a well wherein it floats on the fused salt. This invention provides an improved ladle for removing the metal from the fused salt with less effort and with less loss of metal.

While the ladle is useful for removing any light metal, that is any metal lighter than the fused salt, from fused salt, whether the metal is produced by chemical reduction or by electrolysis, it is especially advantageous in the removal and separation of magnesium produced by electrolysis of magnesium-chloride fusions.

In present practices, floating molten magnesium is removed from the fused salt, from which it is produced by electrolysis for example, by skimming with a small iron ladle. One form of ladle for removing the magnesium has a number of small holes in the bottom for effecting a selective separation of the fused salt from the magnesium. The operator scoops a ladle full of magnesium and salt and raises it above the surface of the salt, allowing the fused salt to drain through the small holes. Since the molten magnesium does not wet the iron, very little magnesium drains through the holes if they are small enough. When the ladle is thus emptied of fused salt, it is again immersed and the fused salt is again drained off, leaving more magnesium. This operation is repeated until sufficient magnesium is collected in the ladle to pour into a casting mold. This removal involves a time-consuming and laborious operation and is inefficient in that substantial quantities of magnesium initially separated escape from the ladle before pouring.

This invention provides a ladle which eliminates the aforementioned difficulties with a resulting increase in efficiency manifested by a saving in time, labor and metal removed. The improved ladle of the invention comprises a receptacle for receiving metal and fused salt by skimming, and pump means for withdrawing the fused salt from the receptacle, permitting the

metal to fill the receptacle. In a ladle embodying my invention, I provide a receptacle and a pump in the form of a gas-lift comprising an upright duct adjacent the receptacle which communicates through a small aperture with a bottom portion of the receptacle and a nozzle for injecting gas into the fused salt in the duct for pumping the fused salt from the bottom of the receptacle as the metal and fused salt flow into the receptacle during the immersion of the ladle. The gas for the gas-lift, nitrogen for example, may conveniently be supplied by running a small pipe along the handle of the ladle, into the receptacle and positioning the nozzle in the bottom of the duct.

In one adaptation of the invention, the walls of the receptacle extend above the discharge outlet of the duct, permitting the operator to immerse the ladle in the fused salt and metal until the fused salt and metal flow over the upper edges of the walls while the discharge outlet is submerged below the surface of the fused bath. By operating the gas-lift, the fused salt is forced up through the duct and through the discharge outlet. When metal begins to flow out of the discharge outlet, the receptacle is full of metal.

In an especially advantageous form of ladle embodying the invention, I provide a receptacle having upper walls arranged to extend above the surface of the fused salt when the ladle is immersed for the skimming operation, an inlet opening on one side just below the surface and a duct for the gas-lift, preferably along an opposite side of the receptacle, the discharge outlet of which is also below the surface. This form of ladle is preferably used by immersing it in the mixture of metal and fused salt sufficiently to submerge the inlet opening and discharge outlet while leaving the upper edges of the receptacle walls above the surface. In another adaptation of the invention, I provide a pouring spout opening into the receptacle near its bottom to facilitate pouring of any fused salt remaining from the ladle before pouring the collected metal into a casting mold.

These and other novel features of the invention will be further described in connection with the accompanying drawings, in which:

Fig. 1 is a side view from above, with parts removed, of a ladle embodying the invention;

Fig. 2 is an elevation, partly in section, of another form of ladle embodying the invention.

Fig. 3 is a plan of the ladle illustrated in Fig. 2.

Figs. 4 and 5 are, respectively, an elevation, partly in section and a plan of another form of ladle embodying the invention, and

Figs. 6 and 7 are similar views of still another form of ladle embodying the invention.

The ladle illustrated in Fig. 1 comprises a cylindrical wall 1 having an outwardly flared upper edge 2 and a bottom 3 forming a receptacle 4. Along one side of the cylindrical side wall, an upright duct 5 is provided, as by welding a U-shaped plate 6 to the wall. The duct has a discharge opening 7 which is at an appreciably lower level than the edge 2 and an aperture 8 in the wall 1 provides a communicating passageway between the duct and the receptacle. At a position approximately at right angles to the duct 5, a handle 9 is attached to the wall 1. The nozzle 10 for the gas-lift is located in the lower portion of the duct 5, and as a convenient means of supplying the nozzle with gas, a small pipe 11 is extended along the handle, into the receptacle, and through the opening 8 where it terminates in the nozzle 10. The end of the pipe 11 connects to a valve 12 which is connected to a hose 13 leading to a source of inert gas such as nitrogen.

In using the ladle of Fig. 1 in the removal of magnesium from the well of an electrolytic cell containing magnesium and a fused salt electrolyte, the ladle is immersed in the well to a point where the edge 2 is just beneath the surface. In this skimming operation, the magnesium floating on the surface of the electrolyte, together with some electrolyte, flows into the receptacle 4. The electrolyte settles to the bottom and, when valve 12 is opened, nitrogen is injected through the nozzle 10, withdrawing the electrolyte through the opening 8 and forcing it up through the duct 5, through the discharge outlet 7 back into the electrolyte in the well. When the gas-lift begins to discharge metal through the outlet 7, the valve 12 is shut off and the ladle full of metal is removed from the well for pouring into a mold.

The ladle illustrated in Figs. 2 and 3 is rectangular in cross-section comprising sides 20 and 21, ends 22 and 23, and a flat bottom 24. As shown in Fig. 2, the upper edge of the end 22, sides 20 and 21 and partition 27 extend above the upper boundaries of the inlet opening 29 and the discharge opening 35 and above the normal metal-fused salt level 26 when the ladle is immersed. The upper edge of wall 23 and the upper edges of the laterally extended parts of walls 20 and 21 terminate at 29 forming a rectangular inlet opening 30. The relatively small U-shaped member 32 attached to the wall 22 forms an upright duct 33 closed at its lower end which communicates with the bottom of the receptacle through the opening 34 in the wall 22. The nozzle 36 for the gas discharge is at the end of the small pipe 37 which extends along the wall 22 in the receptacle and through the opening 34. The handle 38 for the ladle is attached to the wall 22 and the pipe 37 is preferably extended along the handle to the valve or gas cock 39. The valve is connected to a hose 40 which leads to a source of nitrogen or other inert gas. In order to facilitate the pouring of metal out of the receptacle, a spout 41 is formed on the wall 21 at the upper edge 29.

By way of example, a ladle of the type illustrated in Figs. 2 and 3 may have the following approximate dimensions in inches: Length along the bottom—8; width between walls 20 and 21—5;

diameter of duct 23—1½; diameter of pipe 36—½; height of edge 35 and edge 29—6½; height of edge 25—8; hole 34—1 x 1½; top of nozzle above bottom—2.

In using the ladle illustrated in Figs. 2 and 3 in the removal of magnesium from the well of an electrolytic cell containing magnesium metal and a magnesium chloride fusion, the ladle is immersed in the electrolyte and floating metal as shown in Fig. 2, the metal-electrolyte level being indicated at 26. This permits the molten magnesium and fused salt electrolyte to flow from the surface of the body into the receptacle 28 through the openings 30 and 35. Since the edge 25 extends above the level 26, the metal floating on the top of the material collecting in the ladle is prevented from floating away. When the receptacle is filled to the level 26, the valve 39 is opened and nitrogen is injected through duct 33 at a moderate rate, so as not to create turbulence, pumping electrolyte from the bottom of the receptacle through the hole 34 and through the discharge outlet 35. The pumping is continued while magnesium and electrolyte continue to flow into the receptacle through the opening 30. More and more metal enters the ladle and the metal-electrolyte interface drops until metal is expelled by the gas-lift. Actually there is no sharp interface, but a zone where separation is taking place. When this zone drops to a level such that metal is expelled by the gas-lift, the ladle is raised somewhat, about two inches, with a ladle dimensioned as above so that no more metal and electrolyte are drawn in, and pumping is reduced with the ladle tilted toward the duct 33 removing substantially all of the electrolyte which entered the ladle before it was raised. The ladle is then lifted from the well. By merely tilting the ladle, the metal is poured through spout 41 into any suitable mold. Pouring is stopped before any electrolyte left in the ladle starts to come over the lip.

The ladle illustrated in Figs. 4 and 5 corresponds to the ladle illustrated in Figs. 2 and 3, in construction and use, except that one end of the opening 30a is covered with a plate 42 and a tube 43 is provided opening at one end through the plate 42 and at the other near the bottom of the receptacle 28a. The tube 43 thus constitutes a pouring spout which, together with plate 42, permits pouring from the bottom of the receptacle 28a of any fused salt left in the ladle before pouring the metal into a mold.

The ladle illustrated in Figs. 6 and 7 is similar, in construction and operation, to that illustrated in Figs. 4 and 5. The bottom pouring spout, however, is constructed of a U-shaped member 44 attached to the wall 21b, closed at its lower end by an extension of the bottom 24b and opening at its lower end into the receptacle 28b through aperture 45.

In Figs. 4 and 5 and in Figs. 6 and 7, the same reference characters with *a* and *b*, respectively, appended designate the same parts designated in Figs. 2 and 3.

I claim:

An improved ladle for removing a light metal from a body of fused salt and metal which comprises a receptacle for receiving metal and fused salt having upper walls arranged to extend above the surface of the body when the ladle is immersed therein, an inlet opening into the receptacle below the upper edge of said walls for metal and fused salt to flow into the receptacle from a place near the surface of the said body, and a gas-lift comprising an upright duct along one side of the re-

ceptacle opening into the bottom of the receptacle for receiving fused salt and a discharge outlet near the level of the inlet opening for discharging the fused salt pumped out of the bottom of the receptacle.
